UNITED STATES PATENT OFFICE

2,443,360

AUTOMATIC LOCK SLIDER FOR SLIDE FASTENERS

Noel J. Poux, Meadville, Pa., assignor to Talon, Inc., a corporation of Pennsylvania

Application April 14, 1944, Serial No. 531,054

16 Claims. (Cl. 24—205.5)

1

This invention relates to sliders for slide fasteners and, particularly, to an improved locking type slider therefor.

It is one of the objects of the present invention to provide an improved self-locking slider which will lock automatically when the slider is tended to be moved in a direction to open the fastener.

It is another object of the invention to provide such an automatic slider having incorporated therewith locking means which is moved to locking position by the fastener elements and which is automatically released when the slider is moved by its attached pull member in either direction.

It is a further object of this invention to provide an improved lock slider having a locking member which contacts the fastener elements so as to lock frictionally the slider against movement with the locking member having a relatively large contacting surface or bearing area so as to provide substantially a positive locking action.

It is still another object of the present invention to provide an improved automatic lock slider which is strong and rugged in its construction and, at the same time, one which is fool-proof, efficient and effective in its use.

Various other objects and advantages of this invention will be more apparent in the course of the following specification, and will be particularly pointed out in the appended claims.

In the accompanying drawings, there is shown for the purpose of illustration, several embodiments which my invention may assume in practice.

In the drawings:

Fig. 1 is a plan view of a slide fastener having a lock slider in accordance with my invention;

Fig. 2 is a sectional view taken on line II—II of Fig. 1 showing the slider of the preferred construction in locked position;

Fig. 3 is a longitudinal sectional view, similar to Fig. 2, showing my improved lock slider in unlocked position;

Fig. 4 is a sectional view taken on line IV—IV of Fig. 2;

Fig. 5 is a perspective view of the locking member incorporated with the slider of my preferred construction;

Fig. 6 is a longitudinal sectional view through the slider similar to Fig. 2, showing a lock slider of a modified construction in accordance with my invention;

Fig. 7 is a perspective view of the locking member incorporated with the modification shown in Fig. 6;

2

Fig. 8 is an enlarged perspective view of a cylindrical rotative or wedging member for use with my improved lock slider;

Fig. 9 is a longitudinal sectional view through the slider of another modification of my invention;

Fig. 10 is a sectional view taken on line X—X of Fig. 9; and

Fig. 11 is a plan view of the locking member incorporated with the modification shown in Figs. 9 and 10.

Referring more particularly to the drawings, there is shown in Fig. 1 a conventional type slide fastener comprising cooperating rows of spaced interlocking fastener elements 2 attached to the opposed beaded edges of tapes or stringers 3. There is supported on the rows of interlocking fastener elements, a slider, generally designated 4, for longitudinal movement in opposite directions to close and open the fastener in a manner well-known to those skilled in the art. Such slider consists generally of a channeled body member having spaced apart upper and lower wings 5 and 6, respectively, flanged at the sides and connected by a neck 7, so as to provide substantially a Y-shaped channel 4a in the slider.

According to the present invention, there is shown in Figs. 2 through 5, a slider of the preferred embodiment of my invention. In this construction, there is arranged in the upper or top wing 5 of the slider body, a longitudinally extending opening 8 which communicates with the channel 4a in the body member. This opening has preferably a rectangular cross-section but may be of any suitable shape. There is arranged in the opening 8, a longitudinally extending locking member or shoe 9 preferably having a substantially flat or planar inner or bottom side as at 10, as shown in Fig. 5. The locking member 9 is supported in the opening preferably by means of a shoulder and ledge arrangement at both the front and rear thereof as at 8a and 8b, respectively. It will be understood that the locking member 10 is slightly smaller than the opening 8 and is floatingly mounted therein for limited longitudinal movement relative to the slider body. In other words, the locking member 9 rests loosely in the opening 8 and is held in position in such a way as to permit limited shifting movement longitudinally for a purpose hereinafter to be described.

There is arranged on the outer side of the upper wing 5, preferably a longitudinally extending lug portion 12 to which a slider actuating or pull member is adapted to be attached in a manner to

be described. There is arranged in the lug 12 forwardly thereof, a recess 13 having an inner wall 13a which recess communicates with the rectangular shaped opening 8 and which is disposed directly opposite the lower end of the locking member. The outer or upper surface 14 of the locking member 9 at a point preferably adjacent the lower end thereof, is inclined toward the upper end of the slider at an acute angle with the horizontal or the axis of the slider. In other words, the upper surface 14 of the locking member 9 is arranged at an acute angle to the upper wall of the recess 13, so as to provide opposed angular surfaces. It has been found that the angle of inclination of the surface 14 or the acute angle at which the top wall of the recess is arranged to the opposed surface of the locking member, should be between 10 and 15 degrees, preferably about 11 degrees for the most satisfactory results.

There is disposed in the recess 13 of the lug 12 between the opposed angular surfaces 14 and 15, a rotative member 16 preferably cylindrical or spherical in shape, such as a roller or ball. If a cylindrical member or roller is used, the outer periphery thereof is preferably milled as at 17, as shown in Fig. 8, so as to prevent any slipping action and to insure rolling movement thereof for a purpose to be described. The rotative member 16, as above stated, is positioned in the recess 13 and is maintained in contact with the opposed angular surfaces 14 and 15, preferably by means of a resilient member such as a spring 18, which is positioned between the lower end wall 15a of the recess 13 and the rotative member, as shown in Figs 2 and 3 of the drawings. The rotative member 16 cooperates with the opposed angular surfaces 14 and 15 to force wedgingly the locking member inwardly into the channel of the slider in a manner hereinafter to be described.

There is carried by the locking member 9 intermediate the length thereof, and positioned at a point preferably immediately rearwardly of the inclined surface 14, an upwardly extending lug portion 19, which extends up into a loop portion 20 arranged transversely through the lug 12 rearwardly of the recess 13 therein. While any conventional pull or slider connecting member may be used to operate the slider, the pull tab or pull member for the purpose of illustration only, is in the form of a substantially rectangular plate and is generally designated 21. On the inner end the pull member 21 is provided with a rectangular aperture 22, which forms at that end, a pair of spaced legs 23 connected by a trunnion 24. The trunnion 24 extends through the loop portion 20 of the lug 12 so as to be loosely and slidably connected to the slider body. Thus, it will be seen that the lug portion 19 of the locking member is disposed in the path of travel of the pull member 21 with which it is adapted to cooperate to unlock the slider in a manner now to be described.

The improved lock slider of my invention functions in the following manner. It will be understood that as the fastener elements 2 progressively pass through the slider, that the lower flat surface 10 of the locking member 9 rests at all times on the fastener elements. When the slider is moved unintentionally in a direction to disengage the fastener elements or open the fastener due primarily to transverse forces being exerted on the sides of the stringers 3, the locking member 9 will shift its position in the opening 8 and move relative to the body of the slider, due to the frictional force existing between the bottom

of the locking member and the fastener elements. Upon such shifting of the locking member, it will be seen that the rotative member 16 will also be moved due to the fact that it is in contact therewith at all times. As the locking member 9 and rotative member 16 move, it will be seen that the locking member will be forced gradually inwardly into the channel of the slider against the fastener elements therein, due to the inclined surface 14 of the locking member which the rotative member follows during its rolling movement. In other words, the rotative member 16, due to the opposed angular surfaces 14 and 15, acts as a wedge when the locking member is shifted, thereby forcing the locking member inwardly of the slider body. When the locking member 9 is moved further into the channel of the slider, it will be seen that the fastener elements 2 are forced against the inner side of the lower or back wing 6 of the slider, thereby locking frictionally the slider against movement, as shown in Fig. 2 of the drawings.

If it is desired to move the slider by means of the pull member 21, it will be seen that as the pull member is pulled downwardly to open the fastener, as shown in Fig. 3, the trunnion 24 strikes the upwardly extending lug 19 of the locking member, thereby tending to move it downwardly relative to the slider body. In such an event, it will be seen that the rotative member 16 will be rolled or moved in the opposite direction or down the inclined surface 14, thereby permitting the locking member 9 again to float in the opening 8 and ride freely over the fastener elements, until the pulling force on the pull member is again released, at which time the locking member will again lock as above described.

In case the slider is moved in the opposite direction so as to engage the fastener elements 2 and to close the fastener, it will be understood that the locking shoe or member 9 merely rides over the fastener elements and a locking action of the slider is not effected. In other words, the inclined surface 14 or the acute angle between the upper surface of the locking member and the top wall of the recess, is so arranged that the rotative member will urge the locking member inwardly into the channel and against the fastener elements only when the slider is moved in a direction to open the fastener. It will be seen that the spring 18 maintains the rotative member 16 against the opposed angular surfaces 14 and 15 at all times and returns the same to its normal position simultaneously with the movement of the locking member 9 to the unlocked position.

In Figs. 6 and 7 of the drawings, there is shown a slight modification of my improved lock slider. This construction is substantially the same as the preferred form and differs therefrom only in that the inclined surface instead of being arranged on the locking member, is disposed on the top wall of the recess 13, as at 25, and the opposed or upper surface 26 of the locking member 9' is substantially flat or planar, as shown in Fig. 7 and is disposed substantially parallel to the axis of the slider. In other words, the top wall of the recess 13 is inclined toward the top of the slider so as to be disposed at an acute angle with the upper opposed surface 26 of the locking member 9'. It will be understood that this modified slider functions in the same manner as the preferred form. That is to say, the rotative member 16 acts as a wedge to force the locking member 9' into the channel of the slider

against the fastener elements therein when the slider is moved unintentionally in a direction to open the fastener.

There is shown in Figs. 9, 10 and 11 another modified lock slider construction in accordance with the teachings of my invention. In this construction, the locking member 9" is preferably Y-shaped so as to provide opposed yoke-like portions 27 on one end thereof, as more clearly shown in Fig. 11. In other words, the locking member 9" has a shape corresponding to the Y-shaped channel 4a through the slider body and it follows that a Y-shaped opening 28 is arranged in the top wing of the slider in which the Y-shaped locking member is disposed. As in the previous described embodiments, the locking member of this modification is slightly smaller than the Y-shaped opening 28 in which it is positioned, so as to permit the locking member to shift longitudinally of the slider body in order to effect a locking action as hereinbefore described. There is arranged centrally of the Y-shaped locking member 9", preferably a longitudinally extending groove 29 having substantially a flat bottom wall 29a. There is arranged in the lug 12 on top of the slider body, a longitudinally extending recess 30, which communicates with the Y-shaped opening 28 in the top wing of the slider. The top wall of the recess 30 is relatively long and inclined throughout the length thereof toward the top of the slider, as at 31. There is disposed in the recess 30 a rotative member 32 which may be a cylinder (see Fig. 8) or ball, as in the preferred construction. The rotative member 32 is disposed in the groove 29 of the locking member 9", and this groove acts as a race for the rotative member 32 so as to guide and maintain the same in position in the recess.

As in the preferred construction, the rotative member 32 cooperates with the angularly arranged surface 31 of the recess and the bottom surface 29a of the groove 29 of the locking member to force wedgingly the locking member 9" inwardly of the channel of the slider against the fastener elements therein. In this construction there is also provided a spring 33 which is disposed in the recess 30 between the bottom end wall thereof and the rotative member 32, in order to maintain the same in contact at all times with the inclined surface 31 of the recess and the opposed bottom surface 29a of the groove 29 of the locking member. There is carried by the locking member 9" to either side of the groove 29 preferably, a pair of upwardly extending lug portions 34 which extend up through the top wing 5 of the slider to either side of the lug 12, so as to be disposed in the path of travel of the pull or slider actuating member 21. The pull member or tab 21 in this construction has a pair of opposed trunnions 35 arranged on one end thereof which are adapted to fit around the lug 12 in a well-known manner so as to provide a pull member which is slidable longitudinally of the slider body. The trunnions 35 of the pull member cooperate with the lug portions 34 of the locking member 9" to move the same downwardly relative to the slider body when it is desired to move the locking member 9" to its unlocked position in a manner similar to the preferred construction. This modified lock construction functions in substantially the same manner as the preferred construction. In this latter construction it will be seen a relatively large bearing area of the locking member against the fastener ele-

ments is obtained thereby resulting in a greater frictional force for locking the slider.

As a result of my invention, it will be seen that there is provided a slider having locking means incorporated therewith which will lock automatically and effectively the slider against unintentional movement at any point along the fastener elements. It will also be seen that the improved locking means of my invention can be easily and conveniently incorporated with a conventional type slider without changing materially the design or construction thereof.

While I have shown and described several specific embodiments of my invention, it will be understood that these embodiments are merely for the purpose of illustration and description and that various other forms may be devised within the scope of my invention, as defined in the appended claims.

20 What I claim as my invention is:

1. A slider for slide fasteners of the class described comprising a body member having an interior channel through which the fastener elements pass for engaging and disengaging the same, a locking member floatingly disposed in said body member for limited longitudinal movement relative thereto and bearing against the fastener elements in the channel of said body member whereby said locking member is adapted to be moved by the fastener elements as they pass through said slider, and independent wedging means arranged between an inner wall of said body member and said locking member for urging the locking member toward the fastener elements upon longitudinal movement of the locking member when the slider is moved in a direction to disengage the fastener elements, whereby the locking member is forced against the fastener elements so as to lock frictionally the slider against movement, said locking member adapted to be moved by the fastener elements longitudinally of the slider when the same is moved in a direction to engage the fastener elements whereby the locking member is moved to an unlocked position.

2. A slider for slide fasteners of the class described, as defined in claim 1, wherein the wedging means arranged between the inner wall of the body member and the locking member for urging the locking member toward the fastener elements consists of movable means arranged between an inner wall of said body member and the opposed surface of the locking member with said wall and said surface being inclined relative to each other whereby the locking member is forced inwardly toward the fastener elements when the slider is moved in a direction to disengage the fastener elements.

3. A slider for slide fasteners of the class described, as defined in claim 1, wherein the wedging means arranged between the slider body and the locking member for urging the locking member toward the fastener elements consists of a rotative member arranged between an inner wall of said body member and the opposed surface of said locking member with said wall and said surface being inclined relative to each other whereby said locking member is forced inwardly toward the fastener elements when the slider is moved along the fastener elements in the direction to disengage the same.

4. A slider for slide fasteners of the class described comprising a channeled body member having a pull member slidably connected thereto for movement longitudinally thereof, a locking

member floatingly disposed in said body member for limited longitudinal movement relative thereto and bearing against the fastener elements in the channel of said body member whereby said locking member is adapted to be moved by the fastener elements as they pass through said slider, and rotative means arranged between said body member and said locking member movable relative to both of said members for urging the locking member inwardly of the channel toward the fastener elements upon longitudinal movement of the locking member when the slider is moved in a direction to disengage the fastener elements, whereby the locking member is forced against the fastener elements so as to lock frictionally the slider against movement, said locking member having a portion arranged in the path of movement of the pull member whereby the slider is released upon movement of the pull member in one direction.

5. A slider for slide fasteners of the class described, as defined in claim 4, wherein the rotative means consists of a spherical element which cooperates with a surface of the body member and an opposed surface of the locking member.

6. A slider for slide fasteners of the class described, as defined in claim 4, including a resilient member arranged between an inner wall of the body member and the rotative means for maintaining the said means in position and in contact at all times with the opposed surfaces of said body and locking members so that movement of the rotative means will be assured upon movement of the locking member.

7. A slider for slide fasteners of the class described comprising a channeled body member having a pull member slidably connected thereto for movement longitudinally thereof, a locking member floatingly disposed in said body member for limited longitudinal movement relative thereto and bearing against the fastener elements in the channel of said body member whereby said locking member is adapted to be moved by the fastener elements as they pass through said body member, a rotative member arranged between an inner wall of said body member and the opposed surface of said locking member with said wall and said surface being inclined relative to each other, and a spring arranged between an inner wall of said body member and said rotative member for maintaining the same in position and in contact at all times with the inclined surface and the opposed surface so that movement of the rotative member will be assured upon movement of the locking member, said rotative member due to the cooperation thereof with said wall and said surface adapted to force the locking member inwardly of the channel toward the fastener elements when the slider is moved in a direction to disengage the fastener elements whereby the locking member is forced thereagainst so as to lock frictionally the slider against movement and the rotatable member is simultaneously moved by the locking member against the action of said spring, said locking member having a portion thereof arranged in the path of travel of the pull member whereby the slider is released upon movement of the pull member in one direction.

8. A slider for slide fasteners of the class described comprising a channeled body member, a locking member mounted in said member for limited longitudinal movement relative thereto and bearing against the fastener elements in the channel of said slider, said body member being provided with a recess directly opposite the lock-

ing member, and a wedging member arranged in said recess and movable relative to both said body and locking members and which is adapted automatically to force the locking member against the fastener elements upon movement of said slider therealong.

9. A slider for slide fasteners of the class described comprising a channeled body member, a locking member floatingly disposed in said body member for limited longitudinal movement relative thereto and bearing against the fastener elements in the channel of said slider body, said body member having a recess arranged therein directly opposite the locking member with a wall of the recess and the opposed surface of the locking member being arranged at an acute angle to each other so as to provide opposed angularly arranged surfaces, and a member arranged in said recess between said angularly arranged surfaces and being movable relative to both said body and locking members and, which member cooperates with said surfaces to force wedgingly the locking member inwardly of the channel against the fastener elements so as to lock frictionally the slider against movement therealong.

10. A slider for slide fasteners of the class described, as defined in claim 9, including a resilient member for normally urging the movable member between and in contact with the opposed angularly arranged surfaces.

11. A slider for slide fasteners of the class described in claim 9, wherein the movable member consists of a rotative member which is adapted to roll along the opposed angularly arranged surfaces.

12. A slider for slide fasteners of the class described, as defined in claim 9, including a slider actuating member connected to the slider for moving the same along the fastener elements with the actuating member having an operative connection with the locking member for shifting the same to unlocking position.

13. A slider for slide fasteners of the class described comprising a channeled body member, a locking member floatingly disposed in said body member for limited longitudinal movement relative thereto and bearing against the fastener elements in the channel of said body member, said body member having a recess arranged therein directly opposite the locking member, said locking member having an inclined surface arranged thereon directly opposite said recess, and a rotative member arranged in said recess adapted wedgingly to engage between the inclined surface of said locking member and the opposed wall of said recess to force wedgingly the locking member against the fastener elements so as to lock frictionally the slider against movement therealong.

14. A slider for slide fasteners of the class described comprising a channeled body member, a locking member floatingly disposed in said body member for limited longitudinal movement relative thereto and bearing against the fastener elements in the channel of said body member, said body member having a recess arranged therein opposite the locking member with the wall of the recess directly opposite said locking member being inclined toward the top of the body member, a rotative member arranged in said recess adapted wedgingly to engage between the inclined surface of said recess and the opposed surface of said locking member to force the locking member inwardly against the fas-

tener elements so as to lock frictionally the slider against movement therealong.

15. A slider for slide fasteners of the class described comprising a channeled body member, an opening arranged in said body member and communicating with the channel thereof, a locking member loosely disposed in said opening for limited longitudinal movement relative to said body member and bearing against the fastener elements in the channel of said body member, a lug carried by said body and extending longitudinally thereof, a pull member slidably connected to said lug for moving the slider along the fastener elements, said lug having a recess arranged therein and communicating with said opening, with a wall of the recess and the opposed surface of the locking member in said opening being arranged at an acute angle to each other so as to provide opposed angularly arranged surfaces, a rotative member arranged in said recess between said angularly arranged surfaces and which cooperates with said surfaces to force wedgingly the locking member against fastener elements so as to lock frictionally the slider against movement therealong, and a pro-

jecting portion carried by said locking member and extending into the path of travel of said pull member whereby the locking member is shifted to unlocking position upon movement of said pull member.

16. A slider for slide fasteners of the class described, as defined in claim 15 including a spring arranged in said recess for normally urging the rotative member between and in contact with the opposed angularly arranged surfaces.
